UNITED STATES PATENT OFFICE.

WILLIAM B. HUGHES, OF CLEVELAND, OHIO, ASSIGNOR TO THE WELLMAN-SEAVIER-MORGAN COMPANY, OF CLEVELAND, OHIO.

GAS-PRODUCER.

No. 899,867.

Specification of Letters Patent. Patented Sept. 29, 1908.

Application filed February 19, 1908. Serial No. 416,795.

To all whom it may concern:

Be it known that I, WILLIAM B. HUGHES, a citizen of the United States, residing in the city of Cleveland, county of Cuyahoga, and 5 State of Ohio, have invented certain Improvements in Gas-Producers, of which the following is a specification.

This invention is a gas producer having improvements designed for providing increased efficiency and producing a gas free 10 from tar, by combining air and steam or vapor with and effecting combustion of the hydrocarbons evolved in the production of the gas.

15 In the preferred mode of operation, the fuel is fed through the top of the producer, the bulk of the air and steam is introduced through the bottom, the burning fuel is mechanically agitated, air and steam are introduced through the top of the producer for combination with the hydrocarbons distilled from the burning fuel, and the gaseous products of combustion are discharged by a water cooled conduit having its inlet embedded in 20 the fuel at a region of high temperature through which the tarry matter distilled from the coal at higher regions of lower temperature and combined with air and steam must pass in order to escape, whereby 30 matter passing through the gas outlet is subjected to the high temperature required for complete gasification.

In the accompanying drawings, Figure 1 35 is a vertical sectional view of a gas producer embodying the invention, and Fig. 2 is a plan view thereof.

The producer illustrated has the stationary cover 1 supported by the beams 2, the stationary base 3 supported by the beams 4, 40 and the revoluble body 5 carried by wheels 6 which run on the circular track 7 on the base.

The cover 1, having the cylindrical apron 8 depending in the corresponding water channel 9 on the body to seal the top, is provided with the gas tube 10 which is disposed centrally therein and extends into the body to a level below the contemplated top of the fuel bed in a region of comparatively high 50 temperatures during operation.

The lower part of the tube 10, from the bottom to a point above the cover, is composed of concentric shells 10' forming a chamber 10" for the circulation of a cooling liquid, the latter being introduced by a pipe

11 extending to a point near the bottom of the chamber and the vapor being discharged by an outlet 12 at the top thereof.

A pipe 13, fixed to the cover, provides a passage extending therethrough for the introduction of air into the top of the producer above the body of fuel, and a smaller pipe 14 extends into the pipe 13 for the introduction of steam or vapor.

A poker 15, having trunnions 16 journaled in bearings 17 carried by the cover, extends into the body to a point near or below the inlet to the gas tube, and has its top connected by a link 18 with a revolving crank shaft 19, the poker being oscillated thereby 65 in a plane parallel to and clearing the gas tube so as to slice the fuel introduced to the revolving body through the ports 20.

The body is revolved through a circular rack 21 on a spider 22, which is fixed to the 75 body and carries bearings 23 for the wheels 6, the rack being engaged by a pinion 24 fixed to a shaft 25 revolving in bearings 26 carried by the column 27. The shaft is revolved by the pinion 28 fixed thereon, the 80 pinion 29 engaging the pinion 28, the spur gear 30 fixed to the pinion 29, the pinion 31 engaging the spur gear 30, the spur gear 32 fixed to the pinion 31, and the pinion 32' engaging the gear 32 and fixed on the driving 85 shaft 32''. The pitman 33, having the eccentric connection 34 with the spur gear 32, oscillates the pawl mechanism 35 and revolves the ratchet wheel 36 fixed to the crank shaft by which the poker is oscillated. 90

The body has the cylindrical apron 37, depending in the corresponding water channel 38 on the base, and the depending cylindrical apron 39, forming part of an ash hopper, inside of the channel. 95

The cooling and sealing functions may be effected by water flowing through the pipe 11 into the chamber 10'', thence by the tube 12 into the basin like cover 1, thence by the spout 1' into the channel 9 overflowing into 100 the pocket 9', thence by the pipe 40 into the channel 38 overflowing into the pocket 38', and thence escaping by the pipe 41.

The base is provided with the blast pipe 42 (fed by the air pipe 42' and the steam pipe 42'') terminating in the hooded dome 43 centrally disposed in the ash hopper of the body and carried by the spider 44 on the vertical shaft 45 supported in the blast pipe. Surrounding the dome and fixed thereto, be- 110

neath the body, is the basin or concave table 46 for sustaining the ashes in the body hopper, a radially adjustable bar 47 carried by the base breaking up the column and throwing off the ashes into the hopper 3' of the base when either the body or the table is revolved.

To permit the dome and table to revolve, if desired, the spindle 45 may be revolvably supported on a step bearing 45', and to hold such revolvable parts against revolution a pin 47' carried by the base is movable longitudinally into engagement with the table. The table may be revolved in any known manner, as through the friction of the ashes on revolving the body or when the body is stationary by hand if desired.

Particularly in using bituminous coal, with its tendency to cake and expand, it is essential for satisfactory results to agitate and break up the upper strata, which cannot be satisfactorily done manually, and in the present mode of operation a mechanically operated poker is so placed and used as to effectually break up the distilling coal as the body revolves without interference with the gas tube centrally disposed and extending into the revolving body of fuel so that matter escaping therethrough must pass through a body of incandescent coal; the combination of the tarry matter, air and vapor in the top of the producer being furthered by passing through such incandescent fuel and the actions aided by the operation of the poker.

Having described my invention, I claim:

1. A gas producer having a body, a top

for said body, means whereby one of said parts is revolvable with relation to the other, a gas tube having an inlet below the general level of fuel in said body, and a poker journaled in said top and extending into said body so as to slice the fuel surrounding said tube.

2. A gas producer having a revolvable body, a stationary top for said body, a gas tube extending through said top with an inlet below the general level of fuel in said body, and a poker journaled in said top so as to slice the fuel in said body.

3. A gas producer comprising a body, a top for said body, a gas tube having an inlet below the general level of fuel in said body, a poker journaled in said top and extending into said body, and means for introducing oxygen into the top of said body.

4. A gas producer comprising a revolvable body, a stationary top for said body, a stationary base for said body, blowing mechanism extending by way of said base into said body, an air conduit having a passage through said top into said body, a vapor conduit extending into said air conduit, a gas tube extending through said top to an inlet below the general level of fuel in said body, and a poker journaled in said top.

In witness whereof I have hereunto set my name this 13th day of February, A. D. 1908, in the presence of the subscribing witnesses

WILLIAM B. HUGHES.
